CLAIM

The ornamental design for a battery box as shown and described.

DESCRIPTION

FIG. 1 is a front, right, and top perspective view of a battery box, showing my new design;

FIG. 2 is a rear, left, and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a cross-sectional view thereof, taken along the section line 10-10 as depicted in FIG. 5; and,

FIG. 10 is a perspective view thereof, illustrated in an alternate configuration.

The broken lines in the drawings depict portions of the battery box that form no part of the claimed design.

1 Claim, 10 Drawing Sheets
